UNITED STATES PATENT OFFICE

JOSEPH J. MILLER, OF FRESNO, CALIFORNIA

MACHINE FOR TRADE-MARKING AND GRADE-MARKING LUMBER

Application filed December 5, 1927. Serial No. 237,824.

My invention relates to a machine for trademarking and grademarking lumber at one operation with marks that are distinctive in character, co-related and inseparable 5 from each other.

The primary object of my invention is to provide a simple, quick, cheap, practical method of imprinting on a piece of lumber or other material a trademark declaring its 10 manufacturer and its grade as determined by him, in order that it may bear these marks until the ultimate consumer is reached, thus providing the basis of ethical business methods for the benefit of all concerned. 15

Other objects accomplished, and their bearing upon the primary object of this invention are self-apparent upon the perusal of the following:

20 To date, there has been no method devised to accomplish this purpose that is practical as to method of operation or cost thereof, although much intensive effort and money has been expended to solve the problem. 25

That there is an universal approval of the trade and grademarking of lumber is evidenced by the adoption of the idea officially by several of our large lumber trade associations and by most all manufacturers of 30 prominence. Further, the idea has the endorsement of your own United States Department of Commerce, and a pamphlet, special #580, has been issued on the subject 35 embodying the conclusions of that department after many years of investigation. The Southern Pine Association of New Orleans, La., are marking their product on the end with rubber stamps, but declare it 40 unsatisfactory and once issued a pamphlet offering money prizes in open contest for the most practical suggestions for the solution of the problem. All of the larger mills employ graders who carry a crayon in the 45 hand, or on the end of a stick, and mark the grade on the surface of the lumber as it passes from the mill to kiln or dry yards, and again as it emerges from the planers in manufacture; but this is only a perishable, 50 or easily erased or altered mark that designates grade only. My invention places in the hand of the grader in place of the crayon, a simple, easily operated machine with which he can select his grade mark quickly and imprint at any point on the surface of the piece of lumber an indelible combined trademark and grademark that will remain there legible and unalterable until that piece of lumber has passed clear through to the carpenter who builds the house or to the mechanic who manufacturers it into various other articles.

I accomplish these and other objects self-apparent by means of such structure and relative parts as are fully disclosed in the drawing which forms a part of this specification, in which similar characters of reference designate similar parts throughout said specification and drawing and in which Figure 1 shows a rear view of the device; 55 Figure 2 shows a top plan, revealing the arrangement of the grade mark selective keys, two of the horizontal levers in relation to the locking block and the bell cranks dotted below. Figure 3 is a bottom plan 60 showing the trade mark stamp and the grade mark stamp in its center as it appears when imprinted on a board or other surface, and in dotted lines the grade mark stamp 65 holders in nonoperative or first position with the bell cranks and links attached, also in dotted lines the ink roll mechanism in non-operative position. Figure 4 is a side view showing the entire mechanism in non-operative or first position. Figure 5 is a cross-section of a grade mark stamp holder with 70 the operating shaft hooks in position on the stamp and ready to carry the stamp downward from the holder into contact with the trade mark stamp. Figure 6 is a cross-section of the trade mark stamp with the operating shaft holding a grade mark stamp 75 in position therein, and about to be pressed downward into contact with a surface to be marked. The grade mark stamp holder 80 is shown in section just above and ready to receive the grade mark stamp on the return or upward movement of the operating shaft and return to non-operative position. Figure 85 7 is sectional view of the grade mark 85

stamp holder with the stamp in position therein, and shows the spring operated plungers in place in the groove of the holder and the larger diameter portion of the stamp seated against the shoulder in the holder.

Referring to the drawing, the base frame 14 has attached to its upper end the frame 27. These two frames are provided for and adapted to support and co-relate the position and movement of all other parts, i. e., the frame 14 supports the shaft on which the die holders 3 are mounted to rotate and also supports the shaft 19 on which slides block 18 which carries the two levers 17 between which is supported the ink roll 15; the links 16 attach to the levers 17 and are fulcrumed on the frame 14 as shown; the frame 14 also provides a fulcrum point for the bell cranks 29 and has a hole in its lower face through which the stamps 1 and 2 may seat and come to exact face alignment with the surface to be marked. Frame 27 supports the two shafts 21 upon which the stamp 1 moves vertically, and on its top surface is a boss which acts as a bearing through which the shaft 4 slides vertically; a pin 32 fixed in shaft 4 slides in a vertical slot in said boss and prevents rotation of shaft 4. To the bearing boss described is attached the bracket 9 on which is arranged the bearings for the grade mark buttons 6, a spring 10 between the bearing boss and a collar on shaft 4 acts to return shaft 4 to its upper, or selective, position after each downward, or imprint, stroke. Frame 27 also carries the 4 bosses in which are fulcrumed the levers 8, and provides two supporting bosses for the locking bar 13.

In operation the handle of the machine is 40 grasped by the hand of the operator; with one finger he presses down on one of the buttons 6, bearing the grade mark desired to be imprinted. Through the medium of the link 7, lever 8, link 26, bell crank 29 and link 28, the grade mark holder 3 bearing the grade mark stamp 2 is moved into place directly over the trade mark stamp 1 and by means of the locking bar 13 falling into the notch in the end of lever 8, is locked in that position as shown dotted at A until released by turning the knurled nut 11 in the direction indicated by the arrow or pressing down on another of the buttons 6. Next the machine is placed in contact with 50 a surface to be marked. The handle 5 is pressed down; shaft 4 slides down through the bearing in frame 27. The hooks 12 on the end of shaft 4 snap into the grooves in stamp 2 which is disengaged from the holder 3 and is carried down until it seats in stamp 1; further pressure on the handle 5 carries both stamps 1 and stamps 2 down until they contact with the surface to be marked; now pressure is removed from the handle upon 60 which the recoil of spring 10 causes the

shaft 4 to return to its original position, bringing with it part 2 which is returned to place in holder 3. Part 1 is returned to its first position by springs 22 on guide shafts 21. Part 3 bearing part 2 is returned to first position, upon pressing another of the grade mark buttons on which the cam on the end of lever 8 rotates the locking bar 13 in the direction of the arrow, against the tension of spring 23, unlocking the bar in position A, and allowing spring 25 to return it to original position. It is thus apparent that only one grade mark stamp can be positioned over the trade mark stamp at one time, and that, selection and use of another one automatically returns and the one just used to its original position, and out of the way of the one next to be used and that the holder 3 is safely locked in position until the stamp 2 is replaced therein and the shaft 4 has withdrawn upward out of the way.

Upon movement of part 1 downward ink roll 15 is rolled across the face of both stamps inking the same, and again rolls across the stamps when they return to first position. The levers 16 are fulcrumed on frame 14 and carry at their outer ends levers 17 which are fulcrumed on block 18 and carry at their outer ends the ink roll; the block 18 slides upon shaft 19 against the pressure of spring 20 which returns it to the position shown. Guide shafts 21 are short enough to allow the ink roll to swing clear of part 1 on its downward movement.

While this specification sets forth in detail the present and preferred construction of the device, still in practice such deviations from such detail may be resorted to as do not form a departure from the spirit of the invention as defined by the appended claims.

Having thus described my invention, what I claim as new and useful and desire to protect by Letters Patent, is.

1. In a lumber trademarking and grade-marking machine, a base or frame adapted to mount a trademark stamp above its lower face to slide vertically upon a pair of guide shafts and to mount a plurality of grade-mark stamps in holders rotatable about the vertical shafts upon which they are mounted to bring said stamps into central alignment with the trademark stamp, and adapted to support at its top a plate adapted to provide a bearing for a vertical shaft slidable therein and in center alignment over the trademark stamp below, a vertical shaft positioned therein with a handle attached to its upper end and a pair of hooks pivoted in its lower end adapted to engage with a grade-mark stamp, a coil spring around said shaft between a collar thereon and the bearing for said shaft, said spring operating to return said shaft to its upper position in the bearing, a pin set in said shaft sliding vertically in a slot in said bearing operating

to prevent rotation of said shaft in its bearing, a yoke or guide attached to said shaft bearing and supporting a plurality of rods bearing at their upper ends buttons each bearing a trademark character, and means provided whereby when one of said buttons is pressed downward a trademark stamp holder is brought into central position with the trademark stamp and locked there until released by the pressing of another trademark button.

2. In a lumber trademarking and grade-marking machine, a base or frame adapted to mount a trademark stamp above its lower face, to slide vertically upon a pair of guide shafts and to mount a plurality of trademark stamps in holders rotatable about the vertical shafts upon which they are mounted to bring said stamps into central alignment with the trademark stamp, and adapted to support at its top a plate adapted to provide a bearing for a vertical shaft slidable therein, and in center alignment over the trademark stamp below, a vertical shaft positioned therein with a handle attached to its upper end and a pair of hooks pivoted in its lower end adapted to engage with a trademark stamp, a coil spring around said shaft between a collar thereon and the bearing for said shaft, said spring operating to return said shaft to its upper position in the bearing, a pin set in said shaft sliding vertically in a slot in said bearing operating to prevent rotation of said shaft in its bearing, a yoke or guide attached to said shaft bearing and supporting a plurality of rods bearing at their upper ends buttons each bearing a trademark character, and means provided whereby when one of said buttons is pressed downward, a trademark stamp holder is brought into central position with the trademark stamp and locked there until released by the pressing of another trademark button and in connection therewith, means provided for inking said trademark and trademark stamps.

3. In a lumber trademarking and grade-marking machine, a base, or frame, 14, a trademark stamp 1 mounted vertically slideable therein, a plurality of trademark stamps 2 mounted above said trademark stamp 1 but out of center alignment therewith, means provided to bring any one of said trademark stamps 2 into central alignment with stamp 1 and to position stamp 2 in stamp 1, and then to bring both stamps 1 and 2 into contact with a surface to be marked, and to return both stamps 1 and 2 to their original, or non-operative, position.

4. In a lumber trademarking and grade-marking machine, a base, or frame, 14, a pair of shafts 21 mounted therein a trademark stamp 1 vertically slideable on shafts 21, a boss on frame 14, a shaft in said boss, a plurality of trademark stamp holders 3

rotatably mounted on said shaft, grade mark stamps 2 mounted removably in said holders 3, means provided to position stamps 2 over stamp 1, and means provided to remove stamp 2 from holder 3 and carry it downward to a seat in stamp 1, and means provided to carry both stamps 1 and 2 downward into contact with the surface to be marked, and to return both stamps 1 and 2 to their original positions.
